(57) **CLAIM**

The ornamental design for a display screen, as shown and described.

DESCRIPTION

FIG. 1 is a front-top-left perspective view of a display screen according to the claimed design.

FIG. 2 is a front-bottom-right perspective view of the display screen.

FIG. 3 is a rear-top-right perspective view of the display screen.

FIG. 4 is a rear-bottom-right perspective view of the display screen.

FIG. 5 is a front view of the display screen.

FIG. 6 is a rear view of the display screen.

FIG. 7 is a right side view of the display screen.

FIG. 8 is a left side view of the display screen.

FIG. 9 is a top view of the display screen.

FIG. 10 is a bottom view of the display screen.

FIG. 11 is a right side view of the display screen in a first folded configuration.

FIG. 12 is a right side view of the display screen in a second folded configuration.

FIG. 13 is a rear-right perspective view of the display screen in the second folded configuration with the camera cap removed.

FIG. 14 is a front-left perspective view of the display screen in the second folded configuration with the camera cap removed.

FIG. 15 is an enlarged partial front perspective view of the display screen with the camera in a first rotated configuration with the camera cap removed.

FIG. 16 is an enlarged partial front perspective view of the display screen with the camera in a second rotated configuration with the camera cap removed.

FIG. 17 is an enlarged partial right side view of the display screen with the camera in a third rotated configuration.

FIG. 18 is an enlarged partial right side view of the display screen with the camera in a fourth rotated configuration; and,

(Continued)

FIG. 19 is an enlarged partial rear view of the display screen. The dash-dash broken lines in the drawings illustrate portions of the display screen that form no part of the claimed design.

The dash-dot-dot broken lines in FIGS. 6, 15-19 illustrate boundaries of the enlarged views that form no part of the claimed design.

1 Claim, 15 Drawing Sheets
